UNITED STATES PATENT OFFICE.

CHARLES O. REEPS, OF CHICAGO, ILLINOIS, ASSIGNOR TO THE PROSPERITY COMPANY INC., OF SYRACUSE, NEW YORK, A CORPORATION OF NEW YORK.

FLATWORK IRONER.

Application filed April 14, 1926. Serial No. 101,919.

This invention relates to flat work ironing machines and has for its object a particularly simple and efficient arrangement of the ironing elements or instruments by which a machine of large capacity occupies a comparatively small space and also a particularly efficient and simple construction and arrangement of the ironing instruments by which both sides of the work is ironed or finished.

The invention consists in the novel features and in the combinations and constructions hereinafter set forth and claimed.

In describing this invention, reference is had to the accompanying drawing which is a vertical, longitudinal, sectional view of such ironing machine, parts being omitted.

This ironing machine comprises generally, parallel series of ironing instruments arranged to iron or finish both sides of the work, one series ironing or finishing one side of the work and the other series the opposite side of such work and means for automatically conveying the work from one series to the other.

Preferably, the series of ironing instruments are arranged horizontally, that is, in upper and lower horizontal series.

1 designates generally, the upper series and 2 the lower series, these ironing means or instruments of the series being supported by a suitable frame designated generally 3. The upper series as here shown comprises heated hollow chests or tables 4 which are heated by steam or any other medium and rollers 5 co-acting with the tables, the tables usually having concave ironing faces corresponding to the curve of the rollers 5, that is, the rollers are nested in the concave faces of the chests. The rollers are suitably supported in any well known manner and are acted upon by springs located in the housing 6 in the usual manner. Also, the rollers are power driven in any well known manner.

As ironing machines or so called flat work ironers having similar concave chests and rollers are well known to those skilled in the art and as the manner of mounting and actuating the rollers 5 relatively to the chests 4 is well known, further description is thought to be unnecessary.

The lower series of ironing instruments 2 comprises a flat table or chest or a plurality of tables or chests 7 having upper and lower flat ironing faces, these chests 7 being also steam heated in any well known manner.

The lower series also includes compression rolls 8 located at intervals along the upper face of the tables or chests 7 and conveyor belts 9 and 10 which run over the upper and lower faces of the tables or chests 7 respectively, one run of the belt 9 extending between the rollers 8 and the upper face of the chests or tables 7. The conveyor 9 is guided over suitable idler rolls 12, 13, 14, 15 and 16 carried by the frame and one end portion thereof extends upwardly over a power actuated roller 17 located in position to receive the work from one end of the upper series of ironing instruments.

The belt 10 also extends over similar guide roller 18 or a belt thereon to be described, and rollers 19, 20, 21 and 22 carried by the frame 3 and over a power actuated pulley 23 located above the level of the table 7. Also a conveyor belt 24 has opposite runs thereof opposed to the upward portions 25 and 26 of the belts 9 and 10, this belt 24 running over a power pulley 27 at its upper end and over the idler 18. The belt 10 engages the portion of the belt on the idler 18.

A suitable feed belt 30 is located at the front end of the machine to feed the work to the upper series 1 of ironing instruments, this feed belt being actuated by a power actuated roller 31 over which it runs. The power actuated rollers 17, 27, 23 and 31 as well as the rolls 5 may be actuated in any suitable manner or by any suitable and well known mechanism. It is sufficient for an understanding of this invention to bear in mind that the belts must be driven in some fashion.

The work is guided from the belt 24 to the upper ironing face of the tables or chests 7 by a deflector 32 and from the upper face of the tables 7 to the lower faces thereof, or to the belt 10 by a deflector 33.

In operation, the work is fed by one operator or group of operators on the belt 30 and carried to the first roll 5 and moved by the rotation of the roll 5 over the ironing face of the chest 4 coacting therewith, and is then moved successively between the faces of the rollers 5 and chests 4 of the upper series to the rear end of the frame 5 where the work is passed between the upward extension of the belt 9 or the portion 25 thereof and the conveyor belt 24 and carried thereby to the upper face of the ironing tables or chests 7 where it is carried by the belt 10 over such ironing faces, the work being pressed against

the face by the rolls 8. When the work reaches the front end of the chests 7 it is carried to the opposite or lower face of the tables or chests 7 by the belt 10 and is again 5 conveyed to the rear end of the machine by the belt 10 where it can be removed from the belt 10 or the run 26 thereof by another group of operators.

This machine is particularly advantageous 10 in that it is particularly compact and of great capacity. For instance, the machine here shown is a four roll machine and takes up less space than a six roll flat work ironer of the same capacity. It is also particularly ad- 15 vantageous in that the upper series irons or finishes the lower face of the work while the lower series 2 of the ironing instruments finishes or irons the upper face of the work or the opposite face to that which is ironed by 20 the rolls 5 and chests 4.

What I claim is:

1. A flat work ironer comprising cooper- 5 ating roll and shoe mechanism between which the work is passed to iron one side of the work against the shoe, a platen ironing element having an upper flat ironing face, the platen element being located below the roll and shoe mechanism, conveyor belt means having a downwardly moving run from the 0 delivery end of the roll and shoe mechanism, and a horizontally extending run over the upper face of the platen element and running in the opposite direction to that in which the work travels through the roll and shoe mech- 5 35 anism, a second conveyor belt having an inner downwardly moving run opposed to the downwardly moving run of the former belt to carry the work from the delivery end of the roll and shoe mechanism to one end of the 40 platen element whereby the horizontal run of

the former belt draws the work along the platen element with the opposite side of the work toward the platen element.

2. A flat work ironer comprising cooper- 45 ating roll and shoe mechanism between which the work is passed to iron one side of the work against the shoe, a platen ironing element having an upper flat ironing face and a lower flat ironing face, the platen element being located below the roll and shoe mecha- 50 nism, conveyor belt means having a downwardly moving run from the delivery end of the roll and shoe mechanism, and a horizontally extending run over the upper face of the platen element and running in the oppo- 55 site direction to that in which the work trav- 60 els through the roll and shoe mechanism, a second conveyor belt having an inner down- 65 wardly moving run opposed to the down- 70 wardly moving run of the former belt to carry the work from the delivery end of the roll and shoe mechanism to one end of the platen element whereby the horizontal run of the former belt draws the work along the platen element with the opposite side of the work 75 toward the platen element, the second belt having an outer upwardly moving run and a third conveyor belt having a horizontal run running along the lower face of the platen element and an upwardly extending portion at its opposite ends to coact with the first conveyor at the discharge end of the upper face of the platen element and with the outer run of the second conveyor at the discharge end of the lower face of the platen element.

In testimony whereof, I have hereunto signed my name, at Syracuse, in the County of Onondaga, and State of New York, this 30th day of March, 1926.

CHARLES O. REEPS.
